ROBERT O. LOWREY, OF SARATOGA SPRINGS, NEW YORK.

Letters Patent No. 74,388, dated February 11, 1868.

IMPROVED SPRING-BED BOTTOM.

The Schedule referred to in these Letters Patent and making part of the same.

TO ALL WHOM IT MAY CONCERN:

Be it known that I, ROBERT O. LOWREY, of Saratoga Springs, in the county of Saratoga, and State of New York, have invented certain new and useful Improvements in Spring-Bed Bottoms; and I do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use my invention, I will proceed to describe it.

My invention relates to spring-bed bottoms, and consists of a very simple, cheap, and convenient method of applying the springs to the slats at the head and at the foot of the bedstead, and, at the same time, making those at the head stiffer than those at the foot.

In bed-bottoms, as ordinarily constructed, the springs at the head are of the same strength as those at the foot, and as there is more weight in the upper portion of the body than in the lower, the springs at the head are more compressed than at the foot, when the bed is in use.

In my construction I make the springs at the foot considerably weaker than those at the head, and in this way give the bed-bottom an incline towards the foot. In the drawings—

Figure 1 is a top plan view.

Figure 2 is a longitudinal vertical section on the line *xx* of fig. 1; and

Figures 3, 4, and 5 are views of the springs detached and enlarged.

I first construct a bedstead-frame, *A*, in the ordinary manner, and then across the interior of the head and foot-piece of the frame I attach a series of springs, *B C*, made of ordinary brass or iron spring-wire; and shaped or formed as clearly shown in figs. 3, 4, and 5. Each spring is made of a single piece of wire, formed as shown in all the figures, with the ends *b* bent at right angles, so as to be driven into the bed-frame, as shown in fig. 2, and, at a short distance from the ends, turned into loops large enough to receive screws *d*, as shown in fig. 4, for the purpose of fastening them rigidly to the frame *A*. The portion of the wire between the loops for receiving the screws *d*; I first coil, as shown at *h* in fig. 4, and then bend the remainder of it in the form of a tongue, as shown in all the figures, and with a hook, *a*, on the extreme end of the tongue, as shown in figs. 1 and 2. When the springs are being constructed, I make those intended for the head of the bedstead of heavier wire than the ones to be used for the foot, and consequently stiffer. After the springs are attached to the frame *A*, as shown in figs. 1 and 2, I pass the hook *a* up through rectangular openings, *e*, in each end of the slats *D*, as shown in the same figures. The slats *D* will then rest upon the shoulders *e* of the springs, and be supported by them. If the slats become sprung, or for any other reason it may be desirable to turn them over or remove them, it is only necessary to press down the slat until the hook on the spring is released, and then hold the spring stationary and lift off the end of the slat. The other end of the slat may then be released by simply unhooking it. The slat may then be turned over, or another slat substituted in its place. As the springs at the head are made stiffer than those at the foot, they will yield less when the bed is used, and, under the pressure, the slats will incline, as shown in fig. 2 by the red lines. The springs *B C* may be stiffened by passing an iron rod through the coils and fastening it to them. By this means they would act more together, and would be held in their respective positions. The arms *e* of the springs *B C* are made sufficiently far apart to allow the ends of the slats *D* to pass between them, as shown in fig. 1.

By these arrangements of the springs and slats, I am enabled to make a simple, cheap, durable, and convenient spring-bed bottom.

Having thus described my invention, what I claim, is—

A bed-bottom, consisting of a series of independent slats, *D*, suspended on the stiff springs *B*, at the head, and the weaker springs *C*, at the bottom, substantially as shown and described.

ROB'T O. LOWREY.
